FIG. V.

FIG. VII.

FIG. VIII.

INVENTOR:

RUSSELL SCOTT ELLIS,

*Attala C. Daigle,
Attorney*

UNITED STATES PATENT OFFICE.

RUSSELL SCOTT ELLIS, OF PHILADELPHIA, PENNSYLVANIA.

CONCRETE STRUCTURE.

Application filed March 16, 1925. Serial No. 15,821.

My invention is particularly applicable to the construction of seaside elevated boardwalks, streets, bridges, etc., and includes improved forms of vertical and horizontal building units, and means for assembling them in cooperative connection, such that although they may be left permanently rigidly connected, the connecting means permit the horizontal members to be removed from the vertical members and the latter water jetted out of their sand, or other, foundations; so that the entire structure may be shifted inland or seaward in accordance with changes in the coast line, without loss of any of said concrete unit elements of the structure.

As hereinafter described; my invention includes means for effecting what may be termed mortise and tenon connections between vertical columns or piles and horizontal stringers, cross girders etc., formed of reinforced concrete, of such construction and arrangement that although they may be left permanently rigidly connected, they may be separated without loss of any of them, if and when it is desired to remove or replace the structure of which they are components.

My invention includes the various novel features of construction and arrangement hereinafter more definitely specified.

In said drawings; Fig. I is a plan view of an assemblage of unit concrete elements, in accordance with my invention, which may be the substructure of a boardwalk or bridge.

Fig. II is a side elevation of the structure shown in Fig. I.

Fig. III is a fragmentary transverse sectional view of said structure, taken on the line III, III in Figs. I and II.

Fig. IV is a fragmentary vertical sectional view of one of the junctions of a column and girder, taken on the line IV, IV in Figs. I and III.

Fig. V is a fragmentary transverse sectional view, taken on the line V, V in Figs. I and II.

Fig. VI is a plan view of a column, of the form shown in Fig. II.

Fig. VII is a plan view of a simpler form of column, without capital brackets.

Fig. VIII is a perspective view of one of the metal saddle members, shown in Fig. III.

In said figures; the columns or piles 1 are formed of concrete reinforced by a series of metal rods 2 which extend longitudinally therein and project from the upper end

thereof, and preferably having the projectings ends thereof bent toward each other in conical formed tenons, as indicated at 3, and adapted to extend in a correspondingly shaped mortise socket 5 in a superimposed girder 6. Such columns 1 preferably have capital brackets 8 adapted to extend beneath said girders 6.

Said girders 6 are conveniently formed of rectangular cross section, as indicated in Fig. III, and reinforced by metal rods 10 extending longitudinally therein. Said girders preferably have laterally extending enlargements 11 at the regions of said sockets 5 to afford at least the same strength at those regions as elsewhere throughout their length. Said girders 6 have, at predetermined intervals throughout their length, recesses 12 in their opposite vertical faces adapted to receive projections 14 of metallic saddles formed of complementary members 15 having hangers 16 at their upper portions provided with hooked ends 17 and 18 adapted to interengage at the upper portion of the girders, as indicated in Fig. III. Said saddles have suspension bracket flanges 19 preferably connected with the vertical portions of said saddle members by integral webs 20 and affording supports for cross girders 21 which, as indicated in Figs. II and III, have their opposite ends fitted in the saddle brackets to which they may be rigidly connected by bolts 22 extending therethrough and provided with nuts 23.

Of course, the bolted construction last above described is preferable to tie the structure together. However, said saddle brackets afford adequate support for the cross girders if the latter are not subjected to upward strains. However, such boardwalk and bridge structures are sometimes subjected to upward strain by wave action which would tend to lift and float off the cross girders if they were not tied down by such bolts, or otherwise.

It is to be understood that the columns 1 may be set in the ground in proper position, by water jetting them. Thereupon, the girders 6 may be set upon the rows of columns in the desired position to form the longitudinal, stringer, members of the boardwalk or bridge with the reinforcement tenons 3 in coaxial spaced relation with the sockets 5 in the girders. Thereupon, concrete aggregate is poured into said mortise sockets and rammed to interlock with said

reinforcements so that the concrete thus molded in the sockets becomes an integral part of the column, because of such interlocking with the reinforcements, but does not unite with the precast surface of either the column 1 or the girder 6; but merely forms a tenon 24 on said column; accurately fitting the mortise socket in which it has been thus molded. The described method of forming the tenons 24 is advantageous in that it is impossible to locate piles by water jetting with such accuracy as to permit the fitting of precast tenons on the columns in substantially tight relation with precast mortise sockets in the girders, and the described method of construction of the tenons causes the latter to fit the mortises accurately regardless of the errors in the location of the columns, such errors being compensated by thus forming the tenons in slightly eccentric position with reference to the columns. However, I do not desire to exclude from the scope of my claims, a structure in which the tenons are formed upon the columns before the girders are set thereon, as such construction and arrangement is of course possible although entailing much more difficulty in assembling the elements of the structure than the method above described.

Said saddle members 15 are hooked together in pairs, above the girders 6, and swung down upon the latter into the position shown in Fig. III, in which they are ready to receive the cross girders 21, which hold them in engagement with the girders 6.

When it is desired to disassemble the structure above described; the cross girders 21 may be unbolted and removed from the saddles, the complementary parts of the saddles swung apart to release them from the girders, and the latter uplifted from their seats upon the columns 1, leaving the tenons 24 upon the columns. Each of the columns may then be water jettied out of its set position and removed. However, when it is desired to reassemble the same elements; I find it preferable to shatter the concrete tenons 24 from the reinforcements 3 and to proceed as before to form new tenons 24 thereon by pouring concrete in the mortise sockets of the superimposed girders.

Although I prefer to form the columns 1 of circular cross section and to form the girders 6 of rectangular cross section; it is obvious that they may be otherwise shaped.

Therefore, I do not desire to limit myself to the precise details of construction and arrangement herein set forth, as it is obvious that various modifications may be made therein without departing from the essential features of my invention, as defined in the appended claims.

I claim:

1. In a concrete structure, the combination with a precast longitudinally extending concrete horizontal member of rectangular cross section having a conical mortise socket extending vertically therethrough and having a lateral enlargement at the regions of said socket, and a pair of bracket recesses upon a vertical side thereof; of a vertical precast concrete member having metallic reinforcing members in concentric relation and extending longitudinally therein and projecting from the top thereof; the projecting ends of said reinforcements being converged upwardly, forming a tenon arranged to fit within said socket; and means interlocking said horizontal and vertical members including a concrete tenon molded in said mortise socket in interlocking engagement with said metallic reinforcement tenon.

2. In a concrete structure, the combination with a precast girder element having a mortise socket therein; of a precast columnar element having a metallic tenon element projecting therefrom; said tenon element being adapted to fit in said socket, in spaced relation with the sides of the latter; and means cooperatively connecting said girder and column elements including concrete molded in said socket, in engagement with said tenon element, after said elements are assembled.

3. In a concrete structure, the combination with a precast girder element having a mortise socket therein; of a precast columnar element having a tenon element projecting therefrom; said tenon element being adapted to fit in said socket, in spaced relation with the sides of the latter; and means cooperatively connecting said girder and column elements including concrete molded in said socket, in engagement with said tenon element, after said elements are assembled.

In testimony whereof, I have hereunto signed my name at Philadelphia, Pennsylvania, this sixth day of March, 1925.

RUSSELL SCOTT ELLIS.
